STRINGED MUSICAL INSTRUMENT

Rudolph Dopyera, Los Angeles, Calif.

Application June 24, 1935, Serial No. 28,034

2 Claims. (Cl. 84—1)

This invention relates to improvements in stringed musical instruments.

The general object of the invention is to provide a stringed instrument including a novel diaphragm and electrical pick-up device.

Another object of the invention is to provide an improved body for a stringed instrument.

A further object of the invention is to provide a novel mounting for a pick-up device in a stringed musical instrument.

Other objects and the advantages of this invention will be apparent from the following description taken in connection with the accompanying drawings, wherein:

Fig. 1 is a top plan view of a stringed musical instrument embodying the features of my invention;

Fig. 2 is an enlarged section taken on line 2—2 of Fig. 1;

Fig. 3 is a fragmentary side view of the guitar shown in Fig. 1;

Fig. 4 is a fragmentary enlarged section taken on line 4—4 of Fig. 1;

Fig. 5 is a view similar to Fig. 4 showing a modified form of body joint;

Fig. 6 is an enlarged fragmentary section taken on line 6—6 of Fig. 1;

Fig. 7 is an enlarged fragmentary section taken on line 7—7 of Fig. 3;

Fig. 8 is an enlarged fragmentary section taken on line 8—8 of Fig. 1;

Fig. 9 is an enlarged fragmentary top plan view of the guitar shown in Fig. 1 with the cover and tail piece removed;

Fig. 10 is a bottom plan view of the electrical pick-up unit on a reduced scale;

Fig. 11 is a view similar to Fig. 8 showing a modified type of diaphragm;

Fig. 12 is a view similar to Fig. 8 showing the electric pick-up unit mounted in a different manner;

Fig. 13 is a diagrammatic view showing the method of wiring the electrical pick-up unit;

Fig. 14 is a fragmentary view similar to Fig. 8 showing a modified electric pick-up unit in another mounting, and

Fig. 15 is a section taken on line 15—15 of Fig. 14.

This invention is a continuation in part of my copending application, Serial No. 720,753, filed April 16, 1934, now Patent No. 2,045,265, granted June 23, 1936.

Referring to the drawings by reference characters I have indicated my improved musical instrument generally at 10. As shown the instru-

ment 10 comprises a metal body 12, a neck 13, and a tail piece 14. The neck includes a thickened portion 14^a which is reduced in depth and width as at 14^b to provide an extension 14^c and a shoulder 14^d. The extension 14^c passes through a slot 14^e in the side wall at one end of the body and the shoulder 14^d engages the front portion of the side wall as at 14^f. In this manner, that is by the engagement of the extension 14^c in the slot 14^e and the engagement of the shoulder 14^d with the front portion of the side wall the forward end of the neck piece is firmly secured in place (see Figs. 7 and 8).

The body 12 comprises a peripheral wall 15, a bottom member 16 and a top member 17 all preferably made of metal.

As clearly shown in Fig. 4, portions adjacent the top and bottom of the side wall 15 are set inward to form a top portion 18 and a bottom flange portion 19. The side wall 15 further includes a plurality of spaced panels 20 which are shown as inwardly directed and which serve to stiffen the side wall 15.

The edge portion of the bottom 16 is rolled upward and inward to form a bead 21 and includes an upwardly extending portion to form a flange portion 21'. The edge portion of the top 17 is rolled downward and inward to form a bead 22 and includes a depending portion to form a flange portion 22'.

When assembling the instrument the flange portions 21' and 22' are positioned against the outer surface of flanges 18 and 19 of the wall 15 and adjacent to shoulders 23 at the end of the flange portions 18 and 19, and then the flanges 21' and 22' are preferably spot welded to the flanges 18 and 19 as at 21'' and 22''. Or if desired the liquid solder may be applied to the inner surfaces of the flanges 21' and 22' before they are positioned in place on the side wall 15.

In Fig. 5 I have shown a modified method of securing the top 17 and the bottom 16 to the side wall 15. In this view the flange portions of the side wall 15 are directed outwardly as indicated at 18' and 19' and the flanges 21'' and 22'' are positioned inside of the side wall flanges and adjacent to shoulders 23' at the ends of the flanges 21' and 22' and may be secured as previously described.

The top member 17 includes an upper portion 24 which has a recess 25 therein, the side wall 26 and bottom wall 27 of which are preferably formed integral with the upper portion 24. In the bottom of the recess 25 a recess 28 is provided which includes a wall 29 which is integral with 55

the bottom 27 of the recess 25. The lower edge of the wall 29 is turned inward to form a flange 30 which in turn forms a central aperture 31.

If desired a well member 32 which is made of sheet metal may be positioned between the bottom 16 and the flange 30. As shown the well member 32 includes a side wall 33 having at its upper portion an inturned flange 34 and at its lower portion a similar inturned flange 35. The well flange 34 is soldered or otherwise secured to the flange 30 as at 34' and the well flange 35 is soldered or otherwise firmly secured to the bottom 16 as at 35'.

In the upper portion 24 of the top member 17 intermediate the recess 25 and the neck 13 I have shown a plurality of apertures 36 and a plurality of reduced apertures 37. As shown in Fig. 8 the apertures 36 are formed by drawing inward the metal of the top portion to form downwardly extending collars 38 from which extend a plurality of ribs 39 which are integral with the side walls 38. The reduced apertures 37 are formed by punching out the material of the top portion.

At the neck end of the top member 17 I provide an inclined portion 40. (See Figs. 7 and 8.) As shown the key board portion 40 is formed by pressing the material of the upper portion 24 upward a predetermined distance from the neck end and inclining it inwardly towards the edge 30 of the body.

Positioned in the recesses 25 and 28 I provide a metal diaphragm 41 which includes a concave portion 42 and a convex central portion 43. The outer edge of the diaphragm includes a foot flange 44 which rests on the flange 27. For supporting a bridge member 45 I provide a spider member 46 which includes a plurality of radial legs 47 which rest on the upper ends of a plurality of inwardly pressed portions 48 provided on the diaphragm 41. At the apex of the convex portion 43 of the diaphragm a nut 49 is secured thereto which is engaged by a bolt 50 which passes through the spider member.

Positioned over the spider member 46 I provide a cover member 52. As shown the cover member 52 is made of sheet metal and includes a top portion 53 which in general is upwardly inclined from its outer edge towards the center (see Fig. 8). The diameter of the top portion 53 is greater than the diameter of the recess 25 in the body. At the periphery of the cover member the material of the top portion 53 is bent inwardly to form a seat portion 54 and then bent downwardly to form a flange 55. The seat portion 55 of the cover is adapted to engage the outer face of the upper portion 24 of the top member 17 and the flange 55 is adapted to frictionally engage the inner face of the side wall 26 of the recess 25.

Adjacent the center of the cover 52 I provide a raised bridge portion 56 which is integral with the top portion 53 and includes side walls 57, end walls 58 and a top portion 59. The side walls 57, end walls 58, and the top 59 form a chamber 60 in which the bridge 45 is positioned. The side walls 57 are steeply inclined to meet the top portion 53 (see Fig. 8) while the end walls 58 are gradually sloped to meet the top portion adjacent the periphery of the cover (see Fig. 2). Each of the side walls 57 has an aperture 61 therein through which the playing strings 62 pass.

For securing the cover 52 in position I provide a plurality of bolts 66 each of which is positioned in an aperture provided in a depressed portion 68 of the cover. (See Fig. 6.) Each of the bolts 75 66 is positioned in an aperture 69 in the top mem-

ber 17 and engage a nut 70 which is secured to the top member as by soldering it thereto as at 70'. The cover 52 further includes a plurality of apertures 71 which may be shaped and spaced to form a pleasing design. (See Fig. 1.)

Within the body 12 at the end opposite the neck 13 I provide a wood block 72 which is preferably shaped to snugly fit the contours of the body. (See Figs. 8 and 9.) A portion 73 of the neck 13 extends into the body 12 and abuts against the block 72. For securing the neck portion 73 to the block 72 I provide a metal angle member 74 one flange 75 of which engages the upper face of the neck portion 73 and the other flange 76 of which engages the inner face of the block 72. The flange 75 is suitably apertured to receive the counter-sunk head of a bolt 77 which is positioned in a suitable aperture provided in the neck portion 73 and is engaged by a nut 78 which clamps against the under face of the neck portion 73. The flange 76 is suitably apertured to receive a bolt 79 which extends through a suitable aperture provided in the block 72 to a distance beyond the outer face of the body 12. In the wall 15 and the block 73 I provide a recess 80 in which a nut 81 is positioned and engaged by the bolt 79 to firmly clamp the angle member 74 to the block 72.

The tail piece 14 is suitably apertured to allow the bolt 79 to pass therethrough and beyond the tail piece 14 I provide a nut 82 which firmly clamps the tail piece to the body 12. Furthermore, the tail piece 14 preferably includes a downwardly extending boss 84 which engages the cover 52 (see Fig. 8) thus relieving the bridge 45 of the entire pressure of the strings 62.

Positioned in the diaphragm 41, I provide an electrical pick-up device which is indicated generally at 85. As shown the device 85 includes a permanent magnet 86 of the horse-shoe type which is substantially circular (see Figs. 9 and 10) with the pole ends thereof extending outwardly as indicated at 87. To prevent the pole ends from vibrating when the instrument is played I position a bar 88 of non-ferrous material across the outer faces of the pole ends and a bar 88' of similar material against the inner portion of the magnet 86 and clamp the bars 88 and 88' together with a bolt 89 which is also made of non-ferrous metal.

Positioned on the magnet 86 at each pole thereof I provide a magnet 90, the core 90' of which is connected to its associated pole of the magnet 86. Below the diaphragm 41, I provide a plurality of brackets 90'' which are secured to the bottom 16 by soldering or spot welding them thereto as at 90''. Posts 91 mounted on the brackets 90'' extend through apertures 92 provided in the diaphragm 41 and support the magnet 86. The magnet 86 is secured to the brackets 90'' by bolts 93 which pass through the magnet and the posts. The posts 91 and the bolts 93 are made of non-ferrous material. In the body 12 adjacent the bolt 79 I provide a jack plug 94, (see Fig. 9) the plug opening of which is accessible from the exterior of the body.

As diagrammatically shown in Fig. 13 one end of each of the coils of the magnets is connected by a wire 95. The opposite end of one of the coils is connected by a wire 96 to one terminal of the plug 94 and the opposite end of the other coil is connected by a wire 97 to the other terminal of the plug. In use a jack 98 which is suitably wired to a radio amplifying unit 99 which in turn is suitably wired to a loud speaker 100 is inserted in the plug 94.

In Fig. 11 I have shown a modified diaphragm 102. The diaphragm 102 is similar to one shown and described by me in my co-pending application, Serial No. 693,111, filed October 11, 1933, now Patent No. 2,029,496, granted February 4, 1936 and in general includes a raised convex portion 103 which merges into a central concave portion 104. Adjacent its periphery the diaphragm 102 includes a foot portion 105 which rests on the flange 30 instead of on the flange 27 like the diaphragm 41.

When the diaphragm 102 is used the permanent magnet 86 of the electric pick-up unit 85 is of larger diameter than when the diaphragm 41 is used but otherwise the pick-up unit is similar. The diaphragm 102 like the diaphragm 41 is provided with apertures 105 through which the posts 91 project.

In Fig. 12 I have shown an instrument similar to that previously described but wherein the electric pickup unit is positioned in the body 12 intermediate the diaphragm well and the neck end of the body. The neck is cut away within the body as at 105' to provide space for mounting the pick-up unit.

In Fig. 15 I have shown another type of diaphragm 106 mounted in my improved instrument. In general the diaphragm 106 includes a raised convex portion 107 having adjacent its periphery a foot portion 108 which rests on the flanges 30.

Furthermore in Figs. 14 and 15 I have shown a modified form of electric pick-up unit indicated generally at 109. As shown the pick-up unit 109 includes a permanent magnet 109' of the horse-shoe type and which is similar to the magnet 86 of the pick-up unit 85. The magnet 109' is secured to a non-ferrous base member 110 by screws 111 and the base 110 in turn may be secured to the bottom 16 of the guitar as by soldering or spot welding it thereto as at 111'. Positioned on the magnet 109' at each pole thereof I provide an electro-magnet coil 112 which includes a core member 113. The core member 113 is shown as cylindrical in cross section and extends below the magnet 112 and is positioned in an aperture 114 in the magnet 109'. The lower portion of the core 113 is threaded as at 115 to engage in a similarly threaded aperture 116 in the base 110.

Each core 113 extends upwardly from the magnet 112 and passes through an aperture 117 in the diaphragm 106 and an aperture 118 in the cover 52. On the upper end of each core 113 I provide a cross bar portion 119 which extends transversely of the strings 62 and is positioned thereto below. The cross bars 119 are disposed just below the strings 62 and the cross bars can be turned slightly by means of a wrench applied thereto so that their positions beneath the strings will be varied and thus the tone control may be varied. In the modification shown in Figs. 14 and 15 the neck portion 73 terminates at the front of the well member 32 as shown.

It will be understood that the electro-magnet 15 pick-up units described may be positioned either above or below the diaphragm at any point between the string bridge and the string tension keys.

From the foregoing description it will be apparent that I have invented a novel musical instrument and electric pick-up which can be economically manufactured and which is highly efficient in use.

Having thus described my invention, I claim: 25

1. A musical instrument having a base, side walls and a top, forming a hollow body, said top having an aperture therein, a diaphragm in said hollow body, said diaphragm having an aperture therein, strings disposed above the top of said body, a pickup unit having a core on the interior of said body and secured to the base thereof, said core extending upwardly through the apertures in said diaphragm and said top and terminating below said strings. 35

2. A musical instrument comprising a base, side walls and a top forming a hollow body, a raised convex diaphragm secured to the interior of said body substantially centrally thereof, said diaphragm having an aperture in the wall thereof, 40 said top having an aperture therein in alignment with the aperture in the diaphragm, strings disposed above the top of said body, and a pickup unit having a core on the interior of the body extending through the apertures in the diaphragm and the top and terminating adjacent the strings. 45

RUDOLPH DOPYERA.
